UNITED STATES PATENT OFFICE.

THEOSIS C. SEBRING, OF PUEBLO, COLORADO.

REFUSE AND LOW-GRADE-FUEL BURNING APPARATUS.

1,252,041.

Specification of Letters Patent.

Patented Jan. 1, 1918.

Application filed November 10, 1913. Serial No. 800,143.

To all whom it may concern:

Be it known that I, THEOSIS C. SEBRING, a citizen of the United States, residing at Pueblo, in the county of Pueblo and State 5 of Colorado, have invented a certain new and useful Improvement in Refuse and Low-Grade-Fuel Burning Apparatus, of which the following is a full, clear, and exact description.

10 This invention is an improvement in stoves and furnaces and relates in particular to devices adapted to the burning of refuse, peat, lignite, slack and other low grade fuels.

15 The primary object of the invention is the provision of a combustion chamber into which the air may be introduced centrally and the products of combustion allowed to escape laterally adjacent the bottom of the 20 fuel bed, to the end that the combustion shall be maintained adjacent the bottom of the fuel bed and shall be substantially confined to that portion of the device. The invention also comprises a novel system of 25 dampers for the control of the entering and escaping gases and certain other details of construction which will be later described in the specification and pointed out in the appended claims.

30 In the two sheets of drawings accompanying this application and forming a part hereof

Figure 1 is a side view of a stove embodying my invention, certain of the interior parts being indicated in dotted lines;

35 Fig. 2 is partially a front elevation and partially a central, vertical section of the stove shown in Fig. 1, the body of the stove and the fire pot appearing in central, vertical cross section and the remaining parts being shown in elevation;

40 Fig. 3 is a partial front elevation on an enlarged scale, showing certain details of the damper door and the bustle pipe construction;

45 Fig. 4 is a perspective of the inner, shaking portion of the grate, looking at it from the upper side;

50 Fig. 5 is a perspective of the outer, stationary portion of the grate, looking down on it from above and showing the swinging front section in elevated position;

55 Fig. 6 is a perspective, looking down on it from above, of the base portion of the stove,

showing the ash pan, the means permitting the removal of ashes from the base plate, and the central draft regulating means;

Fig. 7 is a side elevation of the draft regulating cylinder; and

Fig. 8 is an enlarged fragmental view of a portion of the stationary part of the grate showing the means of mounting the swinging portion.

Fig. 9 is a vertical section through the stove casing on the line *a—a* of Fig. 3 looking in the direction of the arrow.

Referring to the drawings, 10 indicates a base which is carried by legs 11 and which forms a support for the remainder of the device. Resting on the base 10 is the body 70 of the stove 12, which in this instance is shown as cylindrical in form though I do not wish to limit myself to any particular shape for this or any of the coöperating parts of my device. A bustle pipe 13 surrounds the major portion of the body of the stove, being omitted only at the front where the damper door 14 is located. Draft ports 15, suitably located at various points in the circumference of the stove body, afford communication between the interior of the body portion below the grate and the bustle pipe; and dampers 16 are provided for controlling these openings. I have shown these dampers as being sliding disks but it will 85 be obvious that any other type of dampers could be employed without in any way departing from my invention. A stack 17, located at the rear of the device, leads from the bustle pipe and affords a means for 90 drawing off the smoke and products of combustion which are drawn into the bustle pipe.

The fire pot 18 is shown in detached view in Fig. 5. The pot tapers as shown toward 95 the bottom, the larger diameter being of a size as to be snugly received into the body portion 12. Legs 19 support the pot with its bottom above the base plate 10. Lugs 20, projecting horizontally inward from the 100 lower surface of the portion 18, form a means of support for the grate 21. This member comprises a perforated, horizontal part 22 and a central, perforated dome 23. This dome has perforations in its sides only, 105 as shown in the drawings, and may be made in the form shown or as an imperforate cone surmounting a perforated cylinder, as de-

sired. Spaced guide lugs 24 project below the bottom of the member 21 and contact with the exterior of the cylinder 25 which projects up from the base plate 10. A shaker lug 26^a extends from the front side of the member 21 in position to be engaged by a suitable tool introduced through the door 14, a notch 26^c being made in the section 37 to permit this shaking lug to pass through.

The bottom plate 10 is provided with a central, circular opening around which there is a cylindrical sleeve 25. Snugly fitting within the sleeve 25 there is a cylindrical draft regulator 26 adapted, when in raised position, to close the openings 27 in the dome 23 and, in its other positions, to partially or entirely leave said openings unrestricted. The draft regulator has a longitudinal partition 28 provided with rack teeth 29 adapted to be engaged by a gear 30 mounted on a shaft 31 journaled in the sleeve 25 and in the rim 32 of the base 10. A hand wheel 33 is mounted on the shaft 31 outside the stove 26 and through these means the draft regulator may be raised and lowered as desired to open or close the openings 27 which control the draft into the fire.

Guide tracks 34 are attached to the under side of the base 10 for supporting the ash pan 35 and perforations 36 are preferably made in the sides of these guides to admit a large amount of air to the ash pan. As shown in Fig. 2, the draft regulator 26 is of such length as to prevent the ash pan being withdrawn except when the regulator is in its raised position, thus making it obligatory to cut off the openings 27 before the ash pan can be withdrawn and preventing fire being dropped to the floor. I prefer to make openings 26^a in the lower part of the member 26 as shown in Fig. 7 so that air may pass into the regulator even if the pan is permitted to become full of ashes.

The front section 37 of the plot 18, having draft openings 37^b therethrough, should preferably be made to swing upwardly in order to permit access to the fire pot to remove clinker which may have formed on the section 21. This is conveniently permitted by making this portion of the pot side separate and mounting it on trunnions 37^b fitting in corresponding sockets 37^a (see Fig. 8) on the adjacent pot sections.

The section 37 when in lowered position abuts against a ledge 38; this ledge serves to close the bottom of the space between the fire pot and the stove body 12 at that point. The sides of this space are closed by the adjacent legs 19 and thus air may be admitted through the upper draft openings 40 in the door 14 and forced to pass through the bed of the fire to obtain access to the flue or stack. As clearly shown in Fig. 3, the lower draft openings 41 are below the ledge 38 and there-

fore air admitted therethrough may pass directly to the flue and thus serve to check the fire.

In the base plate 10 there is an opening closed normally by the cover 42; this cover may be removed to rake ashes which have collected on the plate 10 into the pan 35.

An opening 43 leads from the top of the body portion to the stack 17 and a damper 44 serves to control this opening. A damper 45 on the front of the stove controls an opening which serves to admit air over the fuel. These dampers are provided so that in case fire shall have worked up through the fuel to the top, the fire can be checked by the admission of air on top; and also to provide means for carrying off gases which may distil from the fuel and cause danger of explosion if retained.

The cover 46 of the stove is pivoted at 47 and is as large as the body portion 12, thus permitting the opening of the entire top of the stove to admit baled fuel or the like. Doors 48 are provided in the ends of the bustle pipe for convenience in cleaning.

Operation.

The dampers 16 and 45 having been closed and 43 opened, fire is kindled as in an ordinary stove, the amount of air admitted being controlled through the regulator 26 and the dampers 40 and 41. After the fire is thoroughly kindled, the body portion of the stove is filled with the refuse, slack or the like to be burned and the dampers 16 leading to the bustle pipe are opened and the damper 41 closed. Air is now admitted to the fire through the openings 27 in the dome 23 and, on account of the deep and compact bed of fuel over the fire, the products of combustion must find their exit laterally through the fire, through the sides or bottom of the grate, and then through the bustle pipe to the stack. The amount of the draft permitted can be controlled through the regulator 26, this member being raised or lowered as desired by turning the hand wheel 33. If a still hotter fire than can be had by leaving the openings 27 fully open be desired, additional draft through the fire may be had by leaving the damper 40 open, but under ordinary conditions this is not necessary. When burning fuels which give off gases, it will be found advisable to partially or wholly open the damper 44 and also in some cases to admit a little air through the opening controlled by the damper 45. When it is desired to check the fire, draft through 26 is cut off, 40 closed and 41 opened, thus shutting air off from passing through the fire and permitting it to pass under the grate and directly to the stack.

From the above description it will be seen that I have provided a construction capable of an almost infinite number of adjustments

and adapted to meet all conditions of fire desired or fuel to be burned.

Having thus described my invention, what I claim and desire to secure by Letters 5 Patent is:

1. In a device of the class described, a base plate imperforate except for its central portion, a cylindrical draft regulator substantially closing the central opening in the 10 base plate and extending thereabove, a stove body supported on said base plate, a fire pot supported by the base plate and in spaced relation thereto, a shaking grate closing the bottom of said fire pot, said shaking grate 15 having a central, perforated dome projecting thereabove and located in operative relation to said draft regulator, means for moving said draft regulator to control the openings in said dome, openings in said 20 stove body disposed substantially throughout the circumference thereof and communicating with the space below the fire pot, dampers independently controlling said openings, a bustle pipe communicating with 25 said openings, and a stack communicating with said bustle pipe.
2. In a device of the class described, a base plate imperforate except for its central portion, a draft regulator passing through 30 the central portion of the base plate, a stove body supported on the base plate, a grate supported by the base plate in spaced relation thereto, said grate having a perforated dome extending thereabove and located in 35 operative relation to said draft regulator, means for moving the draft regulator vertically, and an ash pan below said draft regulator, the parts being so located and proportioned that the ash pan can not be removed except when the draft regulator is in 40 elevated position.
3. In a device of the class described, a base plate imperforate except for its central portion, a stove body supported on said base 45 plate, a fire pot supported by the base plate and in spaced relation thereto, a grate closing the bottom of said fire pot, said grate having a central, perforated dome projecting thereabove, a tubular member affording 50 communication between the central opening in the base plate and said dome but closed to the space between the base plate and the grate, openings in the stove body disposed substantially throughout the circumference 55 thereof and communicating with the space below the fire pot, dampers independently controlling said openings, a bustle pipe communicating with said openings, and a stack communicating with said bustle pipe.
4. In a stove structure the combination 60 with a body and a door in said body, said door having an upper and lower set of draft openings therethrough, of a fire pot, supporting legs for said fire pot, said fire pot having a hinged section between a pair of 65 said supporting legs, a horizontal stationary ledge against which the lower edge of the hinged section is adapted to rest, said ledge extending from the fire pot to said door and from one of said pair of supporting legs to 70 the other, whereby the draft from the upper openings through said door will be conveyed through the bed of fire in the fire pot and the draft through the lower openings conveyed to a point below the fire pot, said 75 ledge engaging said door between said sets of draft openings.
5. A stove structure, comprising a base plate, a body portion, a fire pot, means to convey air into the fire pot from a point below the fire pot, and a bustle pipe arranged circumferentially and exteriorly of the body portion and at a point below the upper edge of said fire pot, said body having draft ports communicating with said bustle pipe, whereby the products of combustion in its exit from the interior of the stove body, will be drawn through the side wall of the fire pot and through said ports into the bustle pipe. 80
6. In a stove structure, the combination 90 with a base plate, an ash pan below the base plate a grate above said base plate, and a dome extending upwardly from said grate, the wall of said dome having a plurality of perforations, of a tubular member extending 95 through said base plate, and means to move said tubular member upwardly or downwardly to regulate the draft through said dome, said tubular member preventing the removal of said ash pan when in lowered 100 position and closing said perforations in the dome when in raised position.
7. In a stove structure, a base plate, a grate above said base plate, a dome extending upwardly from said grate, a tubular 105 member extending through said base plate, a partition lengthwise of the tubular member, a rack on said partition, a gear coöperating with said rack and a rod connected to said gear whereby the gear may be rotated 110 to raise or lower the tubular member into or out of said dome.

In testimony whereof, I hereunto affix my signature in the presence of two witnesses.

THEOSIS C. SEBRING.
